ANTIRATTLE DEVICE FOR LOCKS

Allan R. MacLagan, Western Springs, Ill., assignor to Western Electric Company, Incorporated, New York, N. Y., a corporation of New York

Application January 9, 1936, Serial No. 58,313

4 Claims. (Cl. 292—340)

This invention relates to locks, and more particularly to an anti-rattle device for the cash box door of a telephone coin collector.

It is an object of the present invention to provide means for preventing the forcing of locked doors.

In accordance with one embodiment, the invention contemplates the provision of a spring pressed wedge positioned upon the lower housing 10 of a coin collector at an angle to the bolt of a lock on the door of said housing so as to be cammed out of the path of the bolt, and urged into engagement with the side of the bolt when the bolt is in the latching position.

15 A better understanding of the invention will be had by reference to the following drawing, wherein

Fig. 1 is a side view of a telephone coin collector with a portion of the lower housing broken away to disclose the location of the device illustrative of the invention;

Fig. 2 is an enlarged fragmentary sectional view taken on the line 2—2 of Fig. 1 in the direction of the arrows, and

Fig. 3 is a fragmentary sectional view taken on the line 3—3 of Fig. 2 in the direction of the arrows.

Referring now to the drawing wherein like reference characters indicate the same parts in the several views, the numeral 1 indicates generally a telephone coin collector comprising an upper housing 2 and a lower housing 3 in which a coin box (not shown) may be inserted. The lower housing is provided with a door 4 which has secured thereto a lock 5 having a bolt 6 designed to be moved from the position shown in dotted lines (Fig. 3) to the position shown in full lines upon operation of the lock. The lower end of the door 4 is provided with a plurality of extending portions 7 which, when the door is in place in the housing, bear against the rim 8 of an opening 9 formed in the lower housing 3 to receive the door.

The upper portion of the lower housing has a cavity 28 formed therein in which is positioned a coiled spring 29. This coiled spring 29 surrounds an extending portion 10 of a wedge 11, and engages a shoulder 12 on the wedge 11. The wedge 11 is slidably mounted upon an inclined surface 13 milled in the upper portion of the lower housing 3 being held in place by a screw 14 which extends through an elongated slot 15 formed in the wedge 11, and is threaded into the lower housing 3. From the flat surface of the wedge 11 which slides on the surface 13 there is em-

bossed outwardly a portion 16 to provide a surface against which the bolt 6 will bear when the bolt is moved to the position shown in full lines (Fig. 3).

In use the wedge 11 will normally be urged downwardly (Figs. 1 and 3) until the upper edge of the slot 15 engages the upper surface of the shank of the screw 14 and in this position will permit the insertion of the door into its place as shown in Figs. 1 and 3 with the bolt 6 retracted. When the door has been placed in position and the lock is operated with a suitable key, the bolt 6 will be cammed upwardly by the operating parts of the lock which may be of any suitable construction, and in moving upwardly the bolt 6 will strike the edge 17 of the wedge and will cam the wedge upwardly until the point 18 thereof passes off the left edge (Fig. 3) of the bolt 6, whereupon the spring 29 will force the point 18 of the wedge down into engagement with the left hand surface of the bolt, thereby to hold the door tightly up against the rim 8.

The hereinbefore described mechanism will prevent any movement of the door 4 in the opening 9 and will, therefore, render it more difficult for anyone to insert an instrument between the door and the housing to pry the door open and force the lock 5 off the door 4 or break the bolt 6. This arrangement automatically compensates for small variations in the dimensions of the lock 30 and the cooperating parts of the door and housing and renders it unnecessary to maintain precise dimensions in the manufacture thereof.

What is claimed is:

1. A device for cooperating with a lock provided with a bolt having a projecting and a retracted position, comprising a frame having a surface parallel to the direction of travel of said bolt, a recess formed in said frame having an inclined bottom wall at an acute angle to the surface, a slidable member movable in said recess on said inclined wall, and a resilient member for urging the slidable member into engagement with said bolt.

2. A device for cooperating with a lock provided with a bolt having a projecting and a retracted position, comprising a frame having a surface parallel to the direction of travel of said bolt, a recess formed in said frame having an inclined bottom wall at an acute angle to the surface, a slidable member having a slot and being movable in said recess on said inclined wall and guided by the walls of the recess, means extending through the slot in said slidable member to limit its movement, and a resilient mem-

ber for urging the slidable member into engagement with said bolt.

3. A device for cooperating with a lock provided with a bolt having a projecting and a retracted position, comprising a slidable member, an inclined surface disposed at an acute angle with respect to the path of travel of the bolt, said slidable member having a flat central portion slidable on said surface, and raised portions adjacent said central portion for presenting a holding surface to the bolt parallel to the face of the bolt, and means for urging the slidable member toward the bolt.

4. A device for cooperating with a lock provided with a bolt having a projecting position

and a retracted position, comprising a slidable member substantially as wide as the bolt, an inclined surface disposed at an acute angle with respect to the path of travel of the bolt, said slidable member having a flat, slotted central portion slidable on said surface and raised portions adjacent said central portion presenting a holding surface to the bolt parallel to the face of the bolt, a headed stud extending through said slotted central portion and cooperating with said inclined surface to limit the movement of said slidable member, and means for urging the slidable member toward the bolt.
